UNITED STATES PATENT OFFICE.

HARRY PENTON FAIRCHILD, OF NEW YORK, N. Y.

DESIGN FOR A PENCIL-CASE.

SPECIFICATION forming part of Design No. 31,118, dated July 4, 1899.

Application filed May 8, 1899. Serial No. 716,055. Term of patent 3½ years.

To all whom it may concern:

Be it known that I, HARRY PENTON FAIRCHILD, a citizen of the United States, residing in the city, county, and State of New York, 5 have invented and produced a new and original Design for Pencil-Cases, of which the following is a specification, reference being had to the accompanying drawings, forming a part thereof.

- o Figure 1 is a plan view of a pencil-case, showing my new design. Fig. 2 is a sectional view of said pencil-case.

As shown in the drawings, the leading or material feature of my design consists of a 5 series of parallel flutes A B A' B', disposed or arranged as shown in Fig. 1, the alternating flutes A A' being convex in cross-section and the intermediate flutes B B' being, in effect, convex in cross-section. The flutes A o A' are ornamented with engine-turning in a

barley-corn pattern, and the alternating flutes B B' are engraved, chased, or otherwise ornamented, as desired, in a roccoco pattern in low relief, consisting of a series of convoluted and intertwined curves, as shown. The ends 25 of the pencil-case are shown without flutes or ornamentation.

It is apparent that this design is also applicable to penholders, fountain-pen cases, pencils, pocket-knives, and other similar articles. 30

Having thus described my invention, what I claim as new, and desire to secure by Letters Patent, is—

The design for a pencil-case, as herein shown and described.

HARRY PENTON FAIRCHILD.
